Specification of Letters Patent. Patented May 23, 1922.

Application filed May 10, 1920. Serial No. 380,342.

(GRANTED UNDER THE PROVISIONS OF THE ACT OF MARCH 3, 1921, 41 STAT. L. 1313.)

To all whom it may concern:

Be it known that I, FREDERICK BAKER, a subject of the King of Great Britain, residing at Blackheath, in the county of Kent, 5 England, have invented new and useful Improvements Relating to Sewing Machines (for which I have filed application in Great Britain, No. 144, filed January 2, 1919, Patent No. 165,813), of which the following is 10 a specification.

This invention has reference to single thread sewing machines of the kind in which an angularly movable loop drawing device situated beneath the needle plate engages the 15 needle thread at each ascent of the needle and after drawing a loop of thread disengages said loop before the bight has been carried through a semi-circle.

A machine operating on this principle embodies in its construction a stationary device situated adjacent to the loop drawing device and having means for arresting and retaining certain loops which are yieldingly retained in tension thereby while other loops 25 are allowed to pass freely over the device.

The primary object of the present improvements is to provide an improved tension device which shall be capable of operating with great certainty and precision when 30 run at the high speed necessary in sewing machines actuated by power.

A further and important object of the invention is to ensure that the long loop formed in the manner above referred to shall 35 be retained under improved tension as it is taken up stitch by stitch by the sewing.

Further objects are to reduce the extent of the movement of the parts and to generally improve the construction of devices of 40 the aforesaid kind whereby they may be rendered more efficient to the ends in view.

With these and such other objects as may hereinafter appear or are incidental thereto the present invention in its broadest aspect 45 may be said to contemplate a construction of tension device or thread loop detainer wherein the main loop arresting and retaining member or members is or are held substantially stationary within the tension device 50 from the time a long loop is arrested and retained thereby until the bight of the loop is in position for releasing.

Stated more specifically the invention is

embodied in a construction wherein the aforesaid stationary tension device is provided with a slidably mounted element which is normally held in a shrouded position within the casing of the device but is adapted at pre-determined intervals to deliver from one end the bight of one loop and be slidably moved into position, to arrest another long loop at the opposite end whereupon it is returned to its shrouded and loop retaining position and the cycle of operations are repeated.

In one embodiment of the invention the stationary casing of the device is formed with a housing in which is movably or slidably mounted a rod constituting the main loop arresting and retaining element said 70 rod being retained in its shrouded position by a movable element which at predetermined periods is actuated through an appropriate lever or levers operated by a cam on the under shaft of the machine or otherwise in such a manner as to permit said rod under the influence of a suitable spring for example to move longitudinally at the proper moment to arrest a fresh long loop of thread.

In the initial position of the parts one 80 end of the aforesaid rod projects beyond the curved back of the stationary casing in such a manner as to arrest a long loop of needle thread after this latter has been drawn off by the loop drawing device and is being drawn up around and over the casing the bight of said loop being arrested by passing under said rod. Means are provided whereby when this occurs, said rod is returned to its shrouded position and the aforesaid long 85 loop permitted to slide along the rod step by step as the thread is taken up by the sewing. This may be effected by providing a lever or other appropriate device adapted to be actuated in any suitable manner to positively 90 return the rod to the shrouded position.

As the long loop is taken up stitch by stitch by the sewing the bight of said long loop slides along the aforesaid rod until it reaches the end whereupon it becomes released from the rod thereby causing the latter to be free to move into a loop arresting position in due time but is retained by a hook or projection carried by the aforesaid stationary casing. The bight is now in such 105 a position that the point of the needle enters

same at its next descent and the rod being free as above mentioned is then positively actuated to project sufficiently beyond the stationary casing to arrest another long loop 5 and give clearance for the bight of the previous loop to slide off the hook or projection whereupon the cycle of operations is repeated.

As hereinbefore stated the above described 10 tension device is particularly but not exclusively applicable to high speed power machines. With such machines particularly when using certain grades or qualities of thread the bulging strand offered by the 15 needle as it commences each ascent is not always well formed and in such circumstances and where the tension device is in a lateral position with respect to the loop drawing device the bulging strand might 20 miss being engaged and drawn along between the adjacent faces of the two devices and we therefore provide an advance loop engager which enters the loop just ahead of the loop drawing portion of the loop 25 drawing device and carries the bight across to the lower face of the tension device ready for engagement between this face and the adjacent face of the loop drawing device in the known manner.

30 In order that the invention may be clearly understood and readily carried into effect the same will now be described more fully with reference to the accompanying drawings in which:—

35 Figure 1 is a sectional side elevation with the inner face plate removed of one constructional form of our improved tension device and Figure 1^a is an end view.

Figure 2 is a plan corresponding to Figure 1.

Figure 3 is a cross section on the line 3—3 of Figure 1.

Figure 4 is a fragmentary cross sectional view of the device showing a loop engaged 45 thereby.

Figure 5 is similar to Figure 1 but shows the parts in a different position.

Figure 6 is a sectional elevation of certain parts of the machine viewed from the 50 end of the under shaft; the tension device and the advance loop engager are shewn in full lines and the loop drawing device is shewn in dotted lines the latter being in fact removed to expose the other parts.

55 Figure 7 is a longitudinal sectional elevation of the parts shewn in Figure 6.

Figure 8 is a sectional elevation on the line 8—8 of Figure 7.

The general operation of the machine is 60 known by disclosure for example in the specifications of the British prior Patents No. 14661 of 1912 and 22250 of 1913 and need not therefore be fully described. A is the needle, B the loop drawing device C the undershaft on which the device B is mount-

ed and D is the tension device. The tension device D is situated laterally with respect to the loop drawing device and the adjacent co-operating faces of these devices are formed for tongue and groove sliding engagement so that at each reciprocation of the needle a loop of thread is drawn out between the aforesaid co-operating faces and is then released in such a position that in being drawn up it passes around and over the tension device in the known manner.

Referring now to the construction form of the improved tension device D constituting the main features of the present invention it is seen that this comprises the main body 1 of the casing the inner face or cover plate 2 and the movable parts arranged with in consisting of the loop arresting and retaining member in the form of a longitudinally sliding rod 3 a spring controlled rod 85 operating lever 4 a spring controlled tension block 5 on which the rod 3 is slidably mounted a detaining member 6 and an operating lever 7 therefor.

In Figure 1 the rod 3 is in its shrouded position so that sub loops can pass unchecked around and over the whole tension device. A small coil spring 4^x in the hub of the lever 4 urges this lever in the direction of the arrow and the lever itself is forked to embrace and lie in cut away portions of the block 5 and of the rod 3 but the member 6 is kept by the lever 7 in its raised position of obstruction to movement on the part of the rod 3. When however the lever 7 is 100 rocked about its pivot as for example by a cam 8 on a collar 9 on the undershaft C engaging the tail of the lever 7 the member 6 is lowered as shown in Figure 5 and the rod 3 moves outwards under the action of 105 the lever 4. The pointed outward end of the rod 3 then projects through an aperture 11 in the back of the casing ready to engage a loop of thread as the latter is being drawn up around and over the casing.

110 The rod 3 is approximately wedge shape or triangular in cross section as seen clearly in Figure 3, and the adjacent portions of the casing are shaped to form a suitable housing for the rod. The base of the rod 115 is preferably formed with a suitably shaped interconnecting surface co-operating with a correspondingly shaped surface on the tension block. In the construction shown the base of the rod is formed with a tongue or 120 rib 12 and the tension block is formed with a corresponding groove. When a loop has been arrested by the projecting end of the rod 3 and has been fully drawn off the rod is positively returned to its shrouded position by suitable means such as an oscillatory lever 13 as shown in Figure 6 this lever being actuated by a cam 14 on the undershaft C and shaped at its free end to engage a shoulder or abutment 3^a on the rod 3 and 125 130

thereby thrust this rod into its shrouded position where it is retained by the detaining member 6 until again released. The hub of the lever 13 is provided with a spring which 5 normally urges the lever in the direction of the arrow shown in Figure 5 so that the normal position of the free end of the lever 13 is clear of the back of the tension device.

When a loop is being drawn up around 10 and over, the tension device is arrested by the projecting end of the rod 3 its bight slides along the underside of the rod and its strands one on each side of the said projecting end slide over the sides of the latter until 15 they are arrested by the shoulders 11^a of the aperture 11 in the casing. This temporary arrest of the loop determines its final formation and length. When the lever 13 engages the shoulder or abutment 3^a on the rod 3 20 and thereby thrusts this rod inwards and downwards into its housing the temporarily arrested loop strands lying against the shoulders 11^a of the aperture 11 are free to slip over the shoulders into the main narrow 25 gap extending along the back of the casing. The loop then occupies a position indicated roughly and enlarged in Figure 4. It is to be observed that the rod as a whole has necessarily become slightly depressed in its 30 housing to accommodate the thread and that the latter necessarily occupies a tortuous position between the tongue 12 on the rod and the groove on the tension block. The thread by reason of the aforesaid tortuous 35 position and by being pinched between the sides of the rod 3 and its housing is under tension as it slides along the rod. It will be understood that while this loop is passing along the rod 3 and affording what 40 may be termed a main loop, any desired number of subsequent loops may be drawn out and passed around and over the tension device unarrested constituting what may be termed sub-loops which form lock or knotted 45 stitches with the strands of the main loop. It will also be observed that although the detaining member 6 of the tension device is depressed at each revolution of the undershaft the rod 3 does not move into its projecting 50 position because it is held by the tension and friction of the engaged loop.

In view of the fact that whereas the strands of an arrested loop lie more obliquely in the narrow aperture on the back 55 of the casing during the early stages of travel of the loop than during its later stage the underside of the rear end of the rod 3 may be enlarged slightly as shown in Figures 1 and 5 so as to increase somewhat 60 the tension exerted by the rod at this stage.

The main loop finally escapes from the rod 3 and is temporarily retained by a hook or projection 15 on the casing from which it is finally levered off by the strands of a new 65 long loop when the latter has been drawn out

through the bight of the old long loop and is being finally formed and drawn taut on the rod 3 in the next cycle of operations.

As hereinbefore stated it is desirable in some circumstances to ensure the engaging 70 of the bulging strand of thread at each ascent of the needle in advance of its engagement by the actual loop drawing device. One convenient form of means for this advance engagement will now be described. 75 Mounted on the same small shaft 15^a as the lever 13 is a second lever 16 the short arm of which engages a cam 17 on the undershaft whilst its long arm extends upwards close to the loop engaging face of 80 the disc B and is formed at its upper end with a pin or projection 18 on which is mounted a member 19 which we may term the advance loop engager. This advance loop engager 19 is formed with a beak 20 85 which normally lies alongside the inner face of the tension device close to the entrance of the groove 21 with which a tongue on the loop drawing disc cooperates in the known manner to draw out a loop. The cam 17 on 90 the under shaft rocks the lever 16 at each rotation of the loop drawing disc B just as the needle is completing its descent and commencing its ascent and just prior to the passage of the gap in the loop drawing disc 95 across the path of the needle. Consequently the bulging strand of thread at the needle is engaged by the beak 20 and carried across to the inner face of the tension device close to the entrance of the groove 21 where its 100 engagement by the loop drawing disc is ensured. In describing the above details it has been assumed that the tension device is located laterally with respect to the loop drawing device and this is in fact the preferred position but it will be understood that by suitably modifying the shape and constructional details of the device in certain respects the said device can be adapted for riding upon the periphery of the loop drawing device without involving any change or appreciable change in its main functions and mode of operation.

I claim:

1. In a single thread sewing machine, the combination with a reciprocating needle, and the needle plate, of means located below the needle plate for drawing loops of thread from the needle and a thread loop detainer comprising a loop arresting and detaining member which after arresting a loop becomes shrouded and then without itself moving keeps the arrested loop under tension while the bight is being drawn towards the needle until the time of its release. 115

2. In a single thread sewing machine, the combination with a reciprocating needle, and the needle plate, of means located below the needle plate for drawing loops of thread from the needle, and a thread loop detainer 120

125

130

comprising a loop arresting and detaining member which after arresting a loop becomes shrouded and then without itself moving maintains a frictional control on the arrested loop and thereby exerts a detaining force and consequent tension on the loop as it advances towards the needle until the time of its release.

3. In a single thread sewing machine, the combination with a reciprocating needle, and the needle plate, of means located below the needle plate for drawing loops of thread from the needle and a thread loop detainer comprising a casing and a loop arresting and detaining member slidable therein and serving after arresting a loop and becoming shrouded to frictionally retard the movement of the arrested loop along it without itself moving until the time of its release.

20 4. In a single thread sewing machine, the combination with a reciprocating needle, and the needle plate, of means located below the needle plate for drawing loops of thread from the needle and a thread loop detainer comprising a casing, and two slidably interengaging elements therein one of which after arresting a loop becomes shrouded and then without itself moving yieldably detains the loop under frictional restraint between the 25 two elements while its bight is being drawn towards the needle until the time of its release.

5. In a single thread sewing machine, the combination with a reciprocating needle, and the needle plate, of means located below the needle plate for drawing loops of thread from the needle, and a thread loop detainer comprising a casing containing a slidably mounted rod which in one position projects 35 at one end beyond the edge of the casing to arrest a loop and in another position remains stationary in a shrouded position while exerting a frictional restraint upon the movement of the arrested loop along it.

45 6. In a single thread sewing machine, the combination with a reciprocating needle, and the needle plate, of means located below the needle plate for drawing loops of thread from the needle, and a thread loop detainer comprising a casing, a rod slidably mounted 50 therein, means for moving the rod into a position in which one end projects beyond the casing into a loop arresting position, means for thrusting it into a stationary 55 shrouded position after its projected end has arrested a loop, and means for maintaining frictional restraint between the rod and the arrested loop as the latter slides along the rod.

60 7. In a single thread sewing machine, the combination with a reciprocating needle, and the needle plate, of means located below the needle plate for drawing loops of thread from the needle, and a thread loop detainer comprising a casing, a rod slidably mounted

therein, means for moving the rod into a position in which one end projects beyond the casing into a loop arresting position, means for then thrusting the rod into a stationary shrouded position, means for retaining it in that position, means for maintaining frictional restraint between the rod and the arrested loop as the latter slides along the rod, and means for allowing the rod to be again moved into a loop arresting 70 position when the previously arrested loop has passed clear of the rod.

8. In a single thread sewing machine, the combination with a reciprocating needle, and the needle plate, of means located below the needle plate for drawing loops of thread from the needle, and a thread loop detainer comprising a casing, a rod slidably mounted therein, means for moving the rod into a position in which one end projects beyond the casing into a loop arresting position, means for thrusting it into a stationary shrouded position after its projected end has arrested a loop, means for maintaining frictional restraint between the rod and the 80 arrested loop as the latter slides along the rod, and means on the rod for exerting greater restraint upon the loop just prior to its escape from the rod than during the earlier passage of it under frictional constraint along the rod.

9. In a single thread sewing machine, the combination with a reciprocating needle, and the needle plate, of means located below the needle plate, for drawing loops of thread from the needle, and a thread loop detainer comprising a casing, a loop arresting and detaining member slidable therein and serving after arresting a loop and becoming shrouded to frictionally retard the movement of the arrested loop along it without itself moving until the time of its release, and a lever periodically rockable to cause one end to thrust the projecting end of the 100 slidable member into a shrouded position 105 relatively to the casing after each arrested loop is formed.

10. In a single thread sewing machine, the combination with a reciprocating needle, and the needle plate, of means located below the needle plate for drawing loops of thread from the needle, and a thread loop detainer comprising a casing, a loop arresting and detaining member slidable therein and serving after arresting a loop and becoming 115 shrouded to frictionally retard the movement of the arrested loop along it without itself moving until the time of its release, a pivoted lever and means engaging one end of said lever to rock it, the other end of said 120 lever when rocked exerting an inward and downward thrust upon the projecting end of the said slidable member to make it assume a shrouded position.

11. In a sewing machine, the combination 125

with the reciprocating needle and the needle plate, of rotary means located below the needle plate for drawing loops of thread from the needle and effecting an early release of the same, a device located laterally with respect to the rotary means and around and over which the released loops are drawn, and means for engaging the needle thread slightly in advance of the rotary means at 10 each reciprocation of the needle.

12. In a single thread sewing machine of the class described, the combination with the reciprocating needle, the needle plate, a

rotary loop drawing disc of the early release type located below the needle plate, a 15 casing located laterally with respect to the disc, a loop arresting and detaining member mounted in said casing to arrest and yieldingly detain certain loops while allowing others to pass completely around and over 20 the casing, and a loop engaging device rockable to enter a bulging strand of needle thread just in advance of its engagement by the rotary disk.

FREDERICK BAKER.
